UNITED STATES PATENT OFFICE

MORTIMER R. ANSTICE, OF ROCHESTER, NEW YORK

ATTACHABLE REFUSE COLLECTOR AND SEPARATOR FOR VEGETABLE PARING MACHINES

Application filed May 20, 1929. Serial No. 364,678.

This invention relates to improvements in attachable refuse collectors and separators for vegetable paring machines and the primary object of this improvement is to produce a combined collector and separator that is adapted to be applied to any of the various types of paring machines now in use.

Vegetable paring machines of the type to which this invention is to be applied comprise means for paring vegetables by moving them within a cylinder that has its inner side roughened whereby the vegetables are pared by an abrading action. While this method is progressing water is fed to the vegetables within the cylinder preferably from above whereby the ground parings are washed from the vegetables, the refuse consisting of the ground parings and water. Heretofore this refuse has usually been allowed to flow through a suitable connection to the ordinary sewer. It has been found that this refuse clogs up the drainage and because of the nature of the refuse it becomes hardened in the drainage thereby clogging it up. In other instances where there is now sewer drainage the refuse has been otherwise disposed of, but in that event it has been difficult to handle the same.

The object therefore of the present invention is to produce a combined collector and separator for the refuse that can be directly connected with the paring machines now in use and which will serve to separate the water from the solid portion of the refuse and the refuse is collected within the collector whereby it does not pass to the sewer drainage and therefore does not clog it up. When sufficient amount of this solid portion of the refuse is collected then it is readily removable from the combined collector and separator.

The combined collector and separator is so constructed that the water from the refuse flows preferably continually from the collector while the solid portion of the refuse remains within the collector to be afterwards removed therefrom.

In the accompanying drawings, Figure 1 is a vertical central section through a paring machine and my improved combined collec-

tor and separator shown attached to the paring machine.

Figure 2 is an enlarged sectional view taken longitudinally through the improved combined collector and separator. 55

Figure 3 is a central sectional view through a part of the parer base and the said separator showing one manner of connecting the parts.

Figure 4 is a central sectional view showing another manner of attaching the collector 60 to the base of the paring machine.

Figures 5 and 6 show sectional views and illustrate other ways of connecting the collector with the base of the paring machine.

Referring now particularly to Figure 1 in 65 which the ordinary type of paring machine is generally shown. In this Figure 1 is shown a stationary cylinder that is roughened on its inner side as shown. In the lower portion of this cylinder a revolving bottom 2 is 70 shown and it is operatively connected with a vertical shaft 3 passing through a bearing 4 formed in the bottom or base portion 5 of the paring machine. A beveled pinion 6 is attached to the lower end of this shaft and 75 engages a beveled pinion 7 that is driven by a suitable pulley 8. All of the parts thus far described are old and well known to those skilled in this art and need no further description. 80

The vegetables to be pared are fed to the cylinder 1 through a suitable hopper 9 and they fall upon the revolving bottom 2 while at the same time water is fed through a pipe 10 located in the upper portion of the 85 said cylinder. The vegetables are thus agitated within the cylinder upon the bottom 2 which is likewise revolved and the vegetables are continually changing their position and the parings are being ground in the cylinder 90 and the water makes a mixture with the parings and cleans the cylinder forming the refuse that flows around the edges of the bottom to the base portion 5. Ordinarily this refuse flows out through an opening 11 95 to a drainage pipe connected with a sewer (not shown) and passes off through the sewer with the disastrous results hereinbefore referred to.

The present invention consists in provid-

ing a combined collector and separator 12 that is located at one side of the machine and located wholly outside of the said machine. In the form shown in Figure 1 this combined 5 collector and separator has a pipe 13 extending from its inner side and the upper end of this pipe is suitably connected with the outlet 11 whereby the refuse flows through the pipe and into the combined collector and separator 12. This collector and separator has an outlet 14 and this outlet 14 is usually connected with a sewer. In order to prevent the solid matter of the refuse from passing through the said drainage to the sewer I provide 10 means for separating the solid matter from the water. In the construction shown in Figures 1 and 2 there is located a suitable screening member or element 15 which will prevent the solid matter from passing from the collector and separator but will permit the water to readily flow through the drainage outlet 14. This screening member 15 may be placed vertically as shown between suitable ears 16 and when necessary it can 20 be removed by drawing it from the collector and separator.

The top 19 of this collector is removable simply by lifting it from the top thereof by means of a handle 20 and when this top is 30 removed then the interior of the collector and separator is made accessible for any purpose whatever.

From Figures 1 and 2 it will be observed that this collector 12 has its bottom 21 inclined towards an outlet 22 and the outlet is closed by an attachable and detachable member 23. The refuse in a peeling machine comprises of course the ground peeling and parts of the vegetable, which are of greater specific 35 gravity than the water mixed therewith. As a consequence the refuse gravitates to the lower part of the separator, and in operation the heavy parts slide down the bottom 21 which declines from the water outlet to the 40 refuse outlet 22. Also in a separator for peeling machines, it is necessary that it have a large refuse receiving chamber 12 and a small water outlet for the purpose of giving the device a capacity that adapts it as a separator to co-act with a peeling machine, and the bottom being declined away from the water outlet to the refuse outlet causes the 45 refuse to flow from the screen 15 and prevents it from packing against the screen in such a manner as to stop the flow of water through it. In fact, I find that this decline of the bottom is necessary in a separator of the type shown when applied to a peeling machine for the purpose above set forth. The 50 function of this outlet and its detachable cover is to remove the solid portion of the refuse therefrom. Of course the collector and separator is not cleaned while the machine is in operation but only when the machine 55 has ceased running.

It will also be understood that these machines are usually used in hotels and large establishments and that their use is not continuous and hence there is ample opportunity to clean this collector and separator of the 70 solid matter collected therein.

In Figures 1 and 2 the upper end 28 of the inlet pipe 13 is shown bolted to a pipe or nipple 29 that extends upward through the bottom of the base 5. However the different paring machines are differently constructed so far as the outlet pipe is concerned. When the base 5 has an opening in its vertical wall then the collector can be connected with the base by means of a screw-threaded nipple 30 as in Figure 3 that screws into the side wall 31 of the paring machine and the other and outer end of the nipple screws into the side wall 32 of the collector and as shown in Figure 3 there is any desired form of nut 33 that screws on the outer projecting end of the nipple 30 thus clamping the collector and the base tightly together compressing between them a suitable packing 34 thus making a tight joint.

In other instances it may be more convenient to attach this collector to the base 5 by bolts 35 which pass through the wall 34 of the collector and the wall 31 of the base there being between the base and the collector a suitable washer 34 as shown in Figure 3.

In Figure 5 the collector 12 is shown attached to the base 5 by means of bolts 36 that pass through the vertical wall 34 of the collector and 31 of the base portion, a suitable washer 37 being placed between the parts.

In Figure 6 another form is shown for connecting the collector with the base. In this construction the base of the machine has a pipe 38 extending from it and in that event suitable clamping bolts 39 pass through the vertical wall 34 of the collector and the enlarged end 40 of the pipe 38, there being the usual washer 41 located between the said parts.

While I have described this invention in detail yet I do not desire to limit myself to these details, the limitations being indicated in the appended claims.

Having thus described my invention what I claim and desire to secure by Letters Patent is:

1. A separator adapted to receive the refuse from a vegetable paring machine comprising a substantially rectangular receptacle having a perforated vertical partition located near one end of the receptacle thus dividing said vessel into a small chamber and a large chamber, a water outlet located in the lower end of said small chamber, a refuse inlet at the upper portion of the large chamber through which refuse passes from

the paring machine, and the large chamber having at its lowest portion an outlet for the solid portion of the refuse, substantially as described.

5 2. A separator adapted to receive the refuse from a paring machine and separate the water contained therein from the solid portion of the refuse, comprising substantially a rectangular vessel elongated horizontally
10 divided into a small chamber at one end and the opposite end formed into a large chamber, a vertically arranged perforated wall located near one end forming said small chamber in said vessel at one end thereof and a
15 water outlet located in the lower portion of said small chamber, the bottom of the large chamber depressed and having an outlet at its lower portion, a refuse inlet for the large chamber located in the upper portion of said chamber, whereby refuse flows through the inlet into the large chamber and the heavy portions of the refuse sinking in the chamber and the water from the refuse flowing through the said perforated division wall
20 between the small and the large chamber and through the outlet thereof, the parts combined for the purpose set forth.

25 In testimony whereof I hereunto affix my
signature.
